UNITED STATES PATENT OFFICE.

FRIEDRICH WILHELM GUSTAV BRUHN, OF BERLIN-WILMERSDORF, GERMANY.

LOCKING MECHANISM FOR TAXIMETER CONTROL LEVERS.

Application filed March 21, 1925, Serial No. 17,265, and in Germany March 24, 1924.

This invention relates to a locking mechanism for the control lever of a taximeter, adapted to prevent cheating on the part of the vehicle driver, especially to prevent the 5 swinging back of the indicator after an initial forward movement of the indicator has been carried out, and furthermore to prevent the driver from throwing quickly "by mistake" the indicator from its engaged position 10 through the "cash" position into its disengaged position, and, finally, to prevent the driver from suddenly moving the indicator from the engaged position to the disengaged position and thence, just as suddenly, back 15 into the engaged position.

The invention is illustrated by way of example in the drawing in which only the back wall of the taximeter is shown together with the parts that cooperate with the rotatable indicator when it is turned into its different positions. The mechanisms by which the distance covered by the vehicle and the time taken for the drives is measured for the automatic calculation, indication and 20 checking of the fares to be paid and the mechanisms for setting the taximeter for various tariffs and for setting the taximeter to its "cash" position, form no part of the invention and are therefore omitted from 25 the drawing.

Fig. 1 shows the back of the taximeter with the parts in the disengaged position.

In Fig. 2 the parts are shown with the rotatable indicator commencing its downward rotary movement as indicated by the 35 arrow I. This downward rotation of the indicator cannot be continued beyond a certain point until the rotatable signal has been swung back in the direction of the arrow II.

In Fig. 3 the rotatable signal is shown 40 swung down into its horizontal position or engaged position (tariff I). The rotation or setting of the taximeter for tariffs II and III and the return movements from these positions can be carried out in any desired manner and are not illustrated.

In Fig. 4 the rotatable signal has been 45 turned back, i. e. has been turned in the direction of the arrow III into the "cash" position where, for a time, it is locked.

In Fig. 5 the rotatable signal has been 50 turned down again, that is has been turned

in the direction of the arrow IV a short distance.

After a short rotary motion in the direction of the arrow IV the reversing of the double-acting locking pawl is accomplished as illustrated in Fig. 6.

In Fig. 7 the parts are in a position in which they enable the rotatable indicator to 60 be turned upwards, that is in the direction of the arrow V, completely back into its upright position in which all parts assume the positions shown in Fig. 1.

Fig. 8 is a side view of a toothed sector 65 pivoted on the back wall of the taximeter which acts as a member for reversing the double-acting locking pawl or detent.

Fig. 9 is a side view of the double-acting locking pawl or rocking detent. 70

In Figs. 1-4 there are shown a back wall 10 and a casing 11 of a taximeter according to the invention. Journalled in the back wall 10 is a manually rotatable indicator 12 which, when completely raised into its vertical position as shown, strikes against a stop 13. Fixed on the shaft 14 of the indicator is a four-lobed star wheel or cam 15, which, together with a lever 17 that is pressed down against the cam by a spring 16, forms a setting or centering mechanism that effects the proper setting of the indicator in any of the four positions: disengaged, tariff I, tariff II, tariff III. Also fixed on the shaft 14 in a known manner is a locking disk 18 which has, on a part of its periphery, a set of locking teeth 19 and on another part of its periphery a set of oppositely directed locking teeth 20. Pivotaly attached to the back wall 10 is a rocking detent 21 which either 80 engages with the teeth 19 by its tooth 22 or with the other set of teeth 20 on the disk 18 by its tooth 23. A spring dog 24 is arranged to co-operate with the rocking detent 21 in such a manner that when the latter is 85 rocked beyond a certain position in the one direction the dog 24 tends to keep the tooth 23 of the detent 21 in engagement with the one set of locking teeth 20 of the disk 18 and when the rocking detent 21 is oscillated 90 beyond a certain position in the opposite direction the dog 24 tends to keep the tooth 22 in engagement with the other set of teeth 19 of the disk 18.

100

Arranged to rotate on one and the same pin or pivot 25 on the disk 18 are the following parts:

- (1) The stepping pawl 26 which has a 5 rearwardly extending fork. Between the prongs of the fork is a pin 27 that is fixed to the disk 18. A spring tends to turn the stepping pawl 26 so that the right hand prong of the fork lies against the pin 27.
- 10 Fixed to the stepping pawl 26 is an arm 28. The stepping pawl 26 lies in the plane of a toothed sector 29 that is pivoted on the back wall 10. When the manually rotatable indicator is turned downward the stepping 15 pawl 26 engages with a tooth of the sector-shaped ratchet 29 and steps it around. Co-operating with the ratchet 29 is a strong friction spring 30 (see Fig. 8) which, although it does not prevent the ratchet from 20 being stepped around, holds it in any position into which it is forcibly turned. Attached to the ratchet 29 is a pin 31 which lies in the plane of the arm 28. The mechanisms described in this paragraph are for 25 the purpose of reversing the rocking detent in one direction when the rotatable indicator is oscillated to and fro to accomplish a downward rotation of the same through a considerable angle.
- 30 (2) Also pivoted on the pin 25 is a sector-shaped reversing member 32 whose function it is to throw back the rocking detent 21 into the position shown in Figs. 1 and 2 after it has been reversed by the ratchet 29 35 into the position shown in Figs. 3, 4 and 5. A spring 33 tends to turn the sector-shaped reversing member 32 counterclockwise, but this is prevented by a pin 35 on the arm 34 which keeps the reversing member 32 in its 40 raised position shown in Figs. 1 and 2. The reversing member 32 operates when the manually rotated indicator is oscillated to and fro prior to its being swung upward through a considerable angle.
- 45 When the taximeter is in its disengaged position all parts are in the position shown in Fig. 1. The tooth 23 of the rocking detent 21 engages the disk-shaped locking member 18 so that the indicator 12 can only 50 be turned through a small angle in the direction of the arrow I into the position shown in Fig. 2, for when this position is reached the tooth 23 of the rocking detent will strike against a tooth 20 of the locking 55 disk 18. By this short rotary movement of the indicator 12 the stepping pawl 26 is caused to step the ratchet 29 around one step. The indicator must now be rotated back in the direction of the arrow II so as to cause 60 the stepping pawl 26 to seize the next tooth of the ratchet 29. When the indicator is now rotated clockwise again, that is in the direction of the arrow I, the ratchet 29 is turned another step so that it strikes against 65 the pin 36 on the rocking detent 21, thus

causing the latter to rock into its reverse position in which its tooth 22 engages with the tooth 19. The pawl and ratchet 29 may also be arranged so that the indicator 12 has to be oscillated back and forth several times 70 before the rocking detent 21 is tilted over into its reverse position.

When the rocking detent 21 has been reversed as described the indicator can be 75 swung down into its engaged position, that is the position shown in Fig. 3. When the indicator 12 is thus rotated the tooth 22 rides over the teeth 19 and prevents the indicator from being raised again during its transition into the horizontal position shown 80 in Fig. 3.

Just before the indicator reaches the horizontal position shown in Fig. 3 a catch 34 strikes against a pin 37 fixed to the back wall 10. When the indicator is turned completely into its horizontal position (Fig. 3) the catch 34 is rotated around its pivot sufficiently to move the holding pin 35 out of the path of the extension at the left top corner of the sector-shaped reversing member 90 32 so that this latter can be turned through a small angle by the action of the spring 33. The indicator 12 can now be swung further around into the tariff II position or into the tariff III position and to and fro between 95 these positions at will.

Assuming that the taximeter is now to be set to its "cash" and "disengaged" positions, the indicator is swung in the direction of the arrow III into the position shown in Fig. 4. 100 In this position a cam (not shown) fixed to the shaft 14 sets the taximeter by means of suitable intermediate mechanisms to its "cash" position. The indicator 12 cannot however be swung in the direction of the arrow III beyond this position because the tooth 22 of the rocking detent engages with one of the locking teeth 19 (see Fig. 4). But during the movement of the indicator into the position shown in Fig. 4, the sector-shaped reversing member 32 will have dropped behind the pin 38 on the rocking detent 21. When the indicator is now turned through a short angle in the direction of the arrow IV (see Fig. 5) into the position shown in Fig. 6 the sector-shaped reversing member 32 pushes the pin 38 downward and thus tilts the rocking detent 21 back into its former position as shown in Fig. 6, in which 110 its tooth 23 engages with the teeth 20 of the locking disk 18. Further downward rotation of the indicator 12, that is rotation in the direction of the arrow IV, is thus prevented. But the indicator can now be turned up in the direction of the arrow V, 120 see Fig. 7 into the disengaged position during which motion, on account of the engagement of the tooth 23 with the tooth 20 a downward rotation of the partly raised indicator is prevented. When the indicator is 130

thus turned upward the arm 28 strikes against the pin 31 and thereby rotates the sector-shaped ratchet 29 back into its initial position shown in Fig. 1. Just before the 5 indicator reaches its vertical position the sector-shaped reversing member 32 strikes against a pin 39 fixed in the wall 10 and is thus rotated clockwise into a position in which it is held by the pin 35 of the catch 34. 10 From the foregoing description and the drawing it is seen that all the requirements and advantages set forth in the opening statement of the specification are met and obtained by simple and reliable means with- 15 out the aid of a separate clockwork.

I claim:—

1. In a device of the kind described, a manually rotatable indicator for indicating various conditions of the device, a rotary 20 shaft on which said indicator is fixed, a locking member for locking said indicator, said locking member being fixed on said shaft so as to rotate with same and comprising two sets of oppositely operative locking teeth, a 25 pivot, a rocking detent mounted on said pivot and provided with teeth at opposite sides of said pivot, the one tooth co-operating with one said set of teeth and the other tooth co-operating with the other said set of 30 teeth, a spring tilting detent for holding the one or the other tooth of the rocking detent in engagement with the one or other set of teeth of the rotatable locking member, a 35 pawl pivoted on the locking member, a rotary ratchet pivoted adjacent said locking member and having teeth engageable by said pawl, and means for throwing the locking detent out of engagement with the one said set of teeth on the locking member and thus 40 releasing the manually rotatable indicator for a full downward rocking movement after said rotary ratchet has been rotated a plurality of steps by said pawl.

2. In a device of the kind described, a 45 manually rotatable indicator for indicating various conditions of the device, a rotary shaft on which said indicator is fixed, a locking member for locking said indicator, said locking member being fixed on said shaft so as to rotate with same and comprising two sets of oppositely operative locking teeth, a pivot, a rocking detent mounted on said pivot and provided with teeth at opposite sides of said pivot, the 50 one tooth co-operating with one said set of teeth and the other tooth co-operating with the other said set of teeth, a spring tilting detent for holding the one or other tooth of the rocking detent in engagement with the one or other set of teeth of the rotatable locking member, a pawl pivoted on the locking member, a rotary ratchet pivoted adjacent said locking member and having teeth engageable by said pawl, a friction producing 55 spring for keeping the rotary ratchet 60 thus turned upward the arm 28 strikes against the pin 31 and thereby rotates the sector-shaped ratchet 29 back into its initial position shown in Fig. 1. Just before the 5 indicator reaches its vertical position the sector-shaped reversing member 32 strikes against a pin 39 fixed in the wall 10 and is thus rotated clockwise into a position in which it is held by the pin 35 of the catch 34. 10 From the foregoing description and the drawing it is seen that all the requirements and advantages set forth in the opening statement of the specification are met and obtained by simple and reliable means with- 15 out the aid of a separate clockwork.

I claim:—

3. In a device of the kind described, a manually rotatable indicator for indicating various conditions of the device, a rotary shaft on which said indicator is fixed, a locking member for locking said indicator, said locking member being fixed on said shaft so as to rotate with same and comprising two sets of oppositely operative locking teeth, a pivot, a rocking detent mounted on said pivot and provided with teeth at opposite sides of said pivot, the one tooth co-operating with one said set of teeth and the other tooth co-operating with the other said set of teeth, a spring tilting detent for holding the one or the other tooth of the rocking detent in engagement with the one or other set of teeth of the rotatable locking member, a pawl pivoted on the locking member, a rotary ratchet pivoted adjacent said locking member and having teeth engageable by said pawl, means for throwing the locking detent out of engagement with the one said set of teeth on the locking member and thus releasing the manually rotatable indicator for a full downward rocking movement after said rotary ratchet has been rotated a plurality of steps by said pawl.

4. In a device of the kind described, a manually rotatable indicator adapted to be swung from an initial position first into an "engaged" position and then back into a "cash" position, a rotary shaft on which said indicator is fixed, a locking member for locking said indicator, said locking member comprising two sets of oppositely operative locking teeth, a pivot, a rocking detent mounted on said pivot and provided with two teeth at opposite sides of said pivot, the one tooth co-operating with one said set of teeth and the other tooth co-operating with the other said set of teeth, a spring tilting detent for holding the one or other tooth of the rocking detent in engagement with the one or other set of teeth of the rotatable locking member, a pawl pivoted on the locking member, means for throwing the locking detent out of engagement with the one said set of teeth on the locking member and thus releasing the manually rotatable indicator for a full downward rocking movement after said rotary ratchet has been rotated a plurality of steps by said pawl, and an arm fixed to said pawl for restoring the rotary ratchet to its normal position when the manually rotatable indicator is swung back into its initial position.

5. In a device of the kind described, a manually rotatable indicator adapted to be swung from an initial position first into an "engaged" position and then back into a "cash" position, a rotary shaft on which said indicator is fixed, a locking member for locking said indicator, said locking member comprising two sets of oppositely operative locking teeth, a pivot, a rocking detent mounted on said pivot and provided with two teeth at opposite sides of said pivot, the one tooth co-operating with one said set of teeth and the other tooth co-operating with the other said set of teeth, a spring tilting detent for holding the one or other tooth of the rocking detent in engagement with the one or other set of teeth of the rotatable locking member, a pawl pivoted on the locking member, means for throwing the locking detent out of engagement with the one said set of teeth on the locking member and thus releasing the manually rotatable indicator for a full downward rocking movement after said rotary ratchet has been rotated a plurality of steps by said pawl, and an arm fixed to said pawl for restoring the rotary ratchet to its normal position when the manually rotatable indicator is swung back into its initial position.

reversing member pivoted on the locking member so as to rotate therewith, a spring tending to rotate the reversing member, a catch pivoted on the locking member for normally holding the reversing member against rotation by said spring, means for releasing the reversing member from said

catch when the indicator has been swung completely down, and means for restoring the reversing member into engagement with ¹⁰ said catch when the indicator is swung back into its initial position.

In testimony whereof I affix my signature.

FRIEDRICH WILHELM GUSTAV BRUHN.
